US0D1032605S

(12) **United States Design Patent** (10) **Patent No.:** **US D1,032,605 S**
Lamb et al. (45) **Date of Patent:** **** Jun. 25, 2024**

(54) **CRYPTOGRAPHIC KEY GENERATOR**

(71) Applicant: **SECUREXPERTS INCORPORATED**, Kennedy Space Center, FL (US)

(72) Inventors: **Chris Lamb**, Champions Gate, FL (US); **Darnell Washington**, Pensacola, FL (US)

(73) Assignee: **SECUREXPERTS INCORPORATED**, Kennedy Space Center, FL (US)

(**) Term: **15 Years**

(21) Appl. No.: **29/788,933**

(22) Filed: **Aug. 16, 2021**

(51) **LOC (14) Cl. 14-02**

(52) **U.S. Cl.**

USPC **D14/383**

(58) **Field of Classification Search**

USPC D10/49, 50; D13/162, 162.1, 164, 168; D14/168, 218, 300, 383, 384, 385, 386, D14/387; D16/200, 201, 202, 203, 217, D16/218

CPC G07C 9/00158; G07C 9/00563; G07C 9/00571; H04L 63/0861; G06F 21/32

(57) **CLAIM**

The ornamental design for a cryptographic key generator, as shown and described.

DESCRIPTION

FIG. 1 is a perspective view of the cryptographic key generator;

FIG. 2 is a front view thereof;

FIG. 3 is a rear view thereof;

FIG. 4 is a right-side view thereof;

FIG. 5 is a left-side view thereof;

FIG. 6 is a top view thereof; and,

FIG. 7 is a bottom view thereof.

The broken lines depict portions of the cryptographic key generator that form no part of the claimed design.

1 Claim, 7 Drawing Sheets
